UNITED STATES PATENT OFFICE.

HIRAM NOBLE, OF FULTON, AND CHARLES STEWART QUAYLE, OF
ROCK ISLAND, ILLINOIS.

SCRAPER.

No. 834,634.

Specification of Letters Patent.

Patented Oct. 30, 1906.

Application filed May 15, 1906. Serial No. 316,965.

To all whom it may concern:

Be it known that we, HIRAM NOBLE, of Fulton, in the county of Whiteside, and CHARLES STEWART QUAYLE, of Rock Island, 5 in the county of Rock Island, State of Illinois, have invented certain new and useful Improvements in Scrapers, of which the following, when taken in connection with the drawings accompanying and forming a part 10 hereof, is a full and complete description, sufficient to enable those skilled in the art to which it pertains to understand, make, and use the same.

This invention relates to devices used for 15 making level surfaces, principally for making a level surface to hard-wood floors, the same being applied after the floor is laid, and the operation of devices of this character being to scrape and clean the floor in the leveling 20 thereof. Machines of this kind may be used to level other hard-wood surfaces, as counters and the like; and the object of this invention 25 is to obtain a machine by means of which the necessity of hand-scraping a floor or other surface of considerable area is obviated.

A further object of the invention is to obtain a machine of the character named whereby uniform work may be done over the entire surface operated upon when the machine 30 is manipulated by persons not particularly skilled in the art.

A further object of the invention is to obtain a machine whereby a greater area of surface may be leveled in a given time and with 35 greater ease and comfort to the workmen than can be done by hand scraping.

In the drawings referred to, Figure 1 is a side elevation of a machine embodying this invention. Fig. 2 is a plan view of the machine illustrated in Fig. 1; and Fig. 3 is a plan view, on an enlarged scale, of a small portion of adjacent parts of the body part of the frame and the bit-holder of the machine, which are hinged together, such parts being 45 separated to show the manner of making the hinges.

A reference-letter applied to designate a given part is used to indicate such part throughout the several figures of the drawings wherever the same appears.

The frame of this machine preferably consists of side pieces A A and body-piece B, to which body-piece the respective side pieces are secured, as by screws C C C'. The sides

A A are respectively provided with slots D D, 55 which are indicated by dotted lines in Fig. 2 and one thereof shown by full lines in Fig. 1.

E is a roller rotatably mounted on axle or shaft e in sides A A. Sides A A and roller E are preferably covered with rubber, felt, or 60 other suitable material.

The protecting material to sides A A is lettered F F and to the roller is lettered G. It is not necessarily used, of course.

H is the bit-holder of the machine and is 65 hinged at its lower end h to body-piece B in the ordinary way of making a hinge. We prefer to construct the machine so that the screws C' will serve as the pintle of the hinge in addition to serving, along with screws C C, 70 to secure the sides to the body part. To do this, such screws C' C' are screw-threaded at the ends thereof, and the middle abutment of the part of the hinge which is on body part B is provided with a hole having corresponding 75 screw-threads.

The position of the bit-holder H may be changed by turning it on its pintle C', and such bit-holder is held rigidly in an adjusted position by bolts I I, which are pivoted at 80 one end by pivots J J in lugs K K on such bit-holder and which pass, respectively, through apertures provided therefor in body part B, in which body part such bolts are respectively firmly secured by the thumb-nuts L L. 85

We have found that considerable movement in the scraping edge of bit M is very desirable, and we obtain such movement by constructing the bit of spring metal and interposing between such bit and the bit-holder H the rubber N or other elastic material in such manner as to not extend to the lower edge m of the bit. 90

O is a pivoted plate provided with set or 95 lock bolts P P.

Q Q are lugs on bit-holder H, and q q is the pintle or pivot of plate O. Lugs Q Q are respectively placed on the sides of the bit-holder H, so as to extend into the slits D D, and 100 we thereby avoid cutting the bit M away on the sides thereof. By this construction the bit M is quite free in a manner corresponding with the resilience of the material of which the bit is made to yield in the operation of the machine, in addition to having the movement which is due to the resilience of the interposed elastic material N. We prefer to 105

use both the resiliency of the elastic material N (which may be spring metal) and of the bit, as last above described; but it will be readily understood that the machine is operative if but one of the resilient bodies is used in the machine.

R is the handle of the machine and consists of spring part r and grasping part r'. Handle R is bent at r'' and is secured to the body part B by means of bolts S S. Spring part r of the handle is preferably made of spring-steel. The length of the handle is sufficient to enable the operator to grasp it and draw the machine over the surface which is to be cleaned or scraped by the bit M.

In operating this machine the handle is lowered to bring the bit M down to the floor with sufficient force to accomplish the desired result in the scraping of the floor. At 20 times the roller E, which at all times in the operating of the machine acts as a weight, is raised entirely from the floor, at which times the cutting or scraping edge of the bit is the fulcrum on which the machine turns and by 25 which such roller is maintained in a raised position.

The cutting edge of the bit is lettered m. Bit-holder H is adjusted to the proper angle relative to the surface which is to be operated 30 upon, and when this is done it will be found that by simply drawing the machine over such surface a very level, smooth, and clean surface is obtained.

By the use of the coverings F F and G no 35 injury is liable to be done to the mop-boards or other vertical walls surrounding the surface operated on when work is being done adjacent thereto, and by the construction of the machine as hereinbefore described, with the 40 screw-heads of screws C C and C' countersunk, work can be done very closely to such mop-board or other wall.

By loosening lock-bolts P P the bit M may be withdrawn or its position changed. Bolts 45 P P press against the bit M and press the lower edge n of pivoted plate N against such bit, holding it firmly against elastic material N and to bit-holder H.

It will be noted that by making the frame 50 as herein illustrated and described the weight placed on the scraping edge m of bit M in the operation of the machine is, in addition to the weight of the roller E, so much of the weight or force of the operator as is required to be 55 exerted or laid upon the handle R to force such handle down and to raise the weight. It occurs that the weight of roller E is not more than one-half the weight which would be required were the handle R not necessarily 60 forced downward in the operation of the machine. In addition to the advantage obtained as last above stated in this construction, which permits the handle to be pressed downward, there is the additional advantage 65 that the force of the operator is best exerted

downward when drawing the machine toward him in the operation thereof. By this construction, too, the momentum of the machine is less than the same would be were a roller employed of two or more times the weight of 70 the roller used by us.

Having thus described our invention, what we claim as new, and desire to secure by Letters Patent, is—

1. In a machine for leveling hard-wood surfaces, the combination of a frame, a roller rotatably mounted in the frame, a handle to the frame, such handle comprising a spring part and a grasping part, and a scraping-bit in the frame, such bit arranged with the cutting edge thereof between the axis of the roller and the grasping part of the handle so that when the free end of the handle is forced down the scraping edge of the bit constitutes a fulcrum on which the roller is supported; 85 substantially as described.

2. In a machine for leveling hard-wood surfaces, the combination of a frame, a roller rotatably mounted in the frame, a handle to the frame, such handle comprising a spring 90 part and a grasping part, and a scraping-bit in the frame, such bit mounted on an adjustable bit-holder so that the cutting edge of such bit is between the axis of the roller and the grasping part of the handle and when 95 such grasping part is forced down the scraping edge of the bit constitutes a fulcrum on which the roller is supported; substantially as described.

3. In a machine for leveling hard-wood surfaces, the combination of a frame, a roller rotatably mounted in the frame, a handle to the frame, such handle comprising a spring part and a grasping part, and such frame consisting of a body part and sides secured thereto, a bit-holder adjustably mounted in the frame, means to maintain such holder in an adjusted position in the frame, a scraping-bit secured to the bit-holder an elastic body interposed between the bit and the bit-holder, such elastic body arranged so that the lower edge of the bit extends beyond the lower edge of the elastic body, and such bit so mounted that the scraping edge thereof is between the axis of the roller and the grasping part of the handle, so that when such grasping part is forced down the scraping edge of the bit constitutes a fulcrum on which the roller is supported; substantially as described.

4. In a machine for leveling hard-wood surfaces, the combination of a frame, a roller rotatably mounted in the frame, a handle to the frame, such handle comprising a spring part and a grasping part, such frame consisting of a body part and sides secured to such body part, a bit-holder pivotally mounted in the frame, bolts pivotally secured to the bit-holder and extending through the body part of the frame, with thumb-nuts thereon 120

to hold the screw rigidly in an adjusted position, an elastic body, a scraping-bit secured to the bit-holder with the elastic body interposed between it and such bit-holder, such bit so mounted that the scraping edge thereof is between the axis of the roller and the grasping part of the handle, so that when such grasping part is forced down the scraping edge of the bit constitutes a fulcrum on which the roller is supported; substantially as described.

5. In a machine for leveling hard-wood surfaces, the combination of a frame provided with slots in the sides thereof, a handle to grasp to operate the machine, a flexible connection between the handle and the frame, a roller rotatably mounted in the frame, such frame and roller respectively provided

with a covering of elastic material, a bit-holder hinged at its lower end to the frame, means to secure the upper end of the bit-holder in a given position relative to the frame, lugs on the bit-holder movable in the slots in the frame, a plate pivotally attached to the lugs, a set-screw in the plate, elastic material and a scraping-bit, respectively interposed between the bit-holder and plate, such elastic material and bit held in position by the tightening of the set-screw in the plate; substantially as described.

HIRAM NOBLE.

CHARLES STEWART QUAYLE.

In presence of—

C. J. SEARLE,

ROBT. W. OLMSTED.
